PISTON LOCK

Robert R. Grover, West Swanzey, N. H., assignor
of one-half to Reginald L. Grover, West
Swanzey, N. H.

Application May 26, 1950, Serial No. 164,503

1 Claim. (Cl. 121—40)

1

The present invention relates to piston locks and it consists in the combinations, constructions and arrangements of parts herein described and claimed.

There is generally provided an elongated cylinder in which is reciprocally mounted a piston and piston rod of conventional character. Extending centrally and longitudinally from the inner side of the piston is a shaft having mounted a secondary piston at its outer end, thus providing a chamber between the main and secondary piston. A cylindrical separator is slidably mounted upon the shaft and divides the chamber into what may be termed inner and outer compartments, the inner compartment being that adjacent the secondary piston. An integrally formed annular ring extends outwardly from the separator and into a circular locking sleeve. The extension is provided with a plurality of openings, preferably three, in each of which is mounted a steel ball. The locking sleeve is provided with a slight taper which is directed inwardly and the balls are normally held against the tapered portion of the locking sleeve and against the shaft by means of a spring which surrounds the shaft and bears against the extension and against a portion of the locking sleeve. Means is provided for the admission of a fluid such as a liquid or gas through the side of the cylinder and thence through the locking sleeve whereby to move the principal piston and the rod outwardly of the cylinder whereby to clamp or otherwise hold certain devices in clamped condition. The locking means will then hold the device in such locked position after the removal of the fluid pressure. Means is also provided for the application of pressure against the secondary cylinder whereby to release the locking means and permit the piston rod to move inwardly of the cylinder. In modified forms of the invention there is provided a spring loading means for the locking means whereby predetermined loads may be placed upon the locking means.

It is accordingly an object of the invention to provide a device of the character set forth which is comparatively simple in construction and operation and yet effective and efficient in use.

Another object of the invention is the provision of a piston lock having novel means for retaining the same in locked position.

Another object of the invention is the provision of a device of the character set forth having novel automatic locking means forming a part of the invention.

A still further object of the invention is the

provision, in a device of the character set forth, of novel means for placing a predetermined load upon a locking device forming a part of the invention.

Other and further objects of the invention will become apparent from a reading of the following specification taken in conjunction with the drawings, in which:

Figure 1 is a vertical sectional view of an embodiment of the invention.

Figure 2 is a view similar to Figure 1 but showing a modification wherein a spring has been added thereto and which spring provides an additional predetermined load to the locking means shown therein.

Figure 3 is a view similar to Figure 1 but showing a modification wherein the piston rod extends through both ends of the cylinder whereby the device will be actuated in two directions.

Figure 4 is a view similar to Figure 3 but having the modification shown in Figure 2 added thereto.

Figure 5 is an elevational view of a locking sleeve forming a part of the invention.

Figure 6 is a sectional view taken along line 6—6 of Figure 5.

Figure 7 is an elevational view of a chamber separator and ball race forming a part of the invention.

Figure 8 is a sectional view taken along line 8—8 of Figure 7.

Figure 9 is an elevational view of a secondary piston forming a part of the invention, and

Figure 10 is a sectional view taken along line 10—10 of Figure 9.

Referring more particularly to the drawings, there is shown therein a cylinder comprising a forward portion 10 and a rearward portion 11 each respectively provided with a flange 12 and 13 which flanges are interconnected by means of bolts 14 or the like and which have interposed therebetween a sealing ring 15.

A piston rod 16 extends through a centrally disposed bushing 17 in the cylinder and is surrounded with a sealing ring 18 contained in a housing 19 in the outer end of the portion 10 of the cylinder. The inner end of the piston rod 16 is affixed to a piston 20 having an annular groove 21 formed centrally in the outer walls thereof and in which groove is mounted a sealing ring 22.

To the inner side of the piston 20 there is centrally affixed an extension rod 23 which extends inwardly through an opening 24 in a locking sleeve 25 and thence through a chamber sep-

arator 26 and which has affixed to its outer end a secondary piston 27 by means of a nut 28 and lock washer 29. The piston 27 is provided with a sealing ring 30.

The locking sleeve 25 is fixed in position substantially centrally within the cylinder by mounting the same in registering recesses 31 formed in the inner walls of the portions 10 and 11, respectively, of the cylinder.

The separator 26 is provided with an outer sealing ring 32 which bears against the inner walls of the cylinder and an inner sealing ring 33 which bears against the sides of the extension rod 23. The separator 26 is likewise provided with a forwardly extending integrally formed ball race 34 which is provided with a series of openings 35 in each of which is mounted a ball 36:

The locking sleeve is provided with an inwardly extending annular front wall 37 and has formed in its outer periphery an annular groove 38 which is adapted to register with a radial passage 39 formed in the flange 12. A compression spring 40 surrounds the extension rod 23 and bears against the wall 37 at one end and the ball race 34 at its other end.

That portion of the locking sleeve 25 which is remote from the wall 37 is provided with a rearwardly and inwardly tapering inner wall 41.

A passageway 42 extends radially through the flange 13 and communicates with the interior of the cylinder between the separator 26 and the secondary piston 27.

In the operation of this form of the invention, it will be apparent that as fluid under pressure enters the passageway 39 the same will then pass into the groove 38 and thence into the interior of the sleeve 25 through a radial passage 43 formed therein and will thence, because of the opening 24 impinge against the piston 20 and against the separator 26 to move the latter to the right as viewed in Figure 1 of the drawings to thus move the ball race 34 likewise to the right and consequently wedge the balls 36 between the extension rod 23 and the tapered walls 41 of the sleeve 25 to thus lock the separator 26 effectively with the sleeve 25 and that such action on the part of the balls 36 is assisted through the action of the compression spring 40.

It will also be seen that additional pressure upon the fluid moving through the passageway 39 will cause the piston 20 and consequently the rod 16 to be moved outwardly of the cylinder to perform desired work such as, for example, the clamping of certain devices in selected positions, the lifting of platforms to desired heights, or the like.

It will also be apparent that when pressure upon the fluid entering the passageway 39 is released that the rod 16 will continue to perform its function and will remain in position due to the fact that any inward pressure upon the rod 16 will act to continue and even to increase the wedging action of the balls 36 between the extension rod 23 and the tapered surface 41 of the sleeve 25.

When, however, it is desired to again move the piston 20 and piston rod 16 to the right as viewed in Figure 1 of the drawings, it is only necessary to admit fluid under pressure into the passageway 42 whereupon the separator 26 will be moved to the left against the action of the spring 40 thereby releasing the wedging action of the balls 36 between the extension 23 and tapered surface 41 and that further pressure upon the fluid entering the passageway 42 will act to move the

secondary piston 27 to the right to thus cause the inward movement of the rod 16 and its attached mechanisms.

In the form of the invention shown in Figure 2 of the drawings the construction is identical with that shown in Figure 1 and similar parts have been given identical reference characters. The difference in this form of the invention lies in the provision of an elongated ball race 34a and the addition of a compression spring 44 having a predetermined strength and which spring surrounds the elongated portion 34a and bears against the sleeve 25 at one end and against a backing plate 45 at its other end. The backing plate 45 in turn bears against the inner end of a recess 46 in which the sleeve 25 is longitudinally slidably in the present form of the invention.

In the operation of this form of the invention, in addition to the functions above described with regard to Figure 1, it will be seen that the spring 44 places an additional and predetermined load upon the balls 36 in their coaction with the extension rod 23 and the tapered surface 41 so that locking sleeve 25 may not be released when pressure is brought to bear against the secondary piston 27 and separator 26 until such pressure is great enough to overcome the strength opposed to it by the spring 44.

In the form of the invention shown in Figure 3 the construction is identical with that shown in Figure 1 with the exception that an intermediate body portion 47 is interposed between the flanges 12 and 13 and is connected to such flanges by bolts 48 and 49, respectively. There is also provided an additional but oppositely acting locking means whose respective parts have each been designated by reference characters identical with those of the originally mentioned locking means but which reference characters each bear the suffix "a." There is also provided a centrally disposed wall 50 within the body 47 through which the extension rod 23 slidably extends and which is provided with a sealing ring 51 which bears against the extension rod. The passageway 39 is provided with a connecting passageway 53 which in turn connects with a passageway 54 which communicates with a passageway 55 which, in turn, connects with a chamber 56 within the body 47 which chamber is bounded by the wall 50 and the separator 26a.

The passageway 42 is connected by a passageway 57 with a passageway 58 in the body 47 and this passageway is interconnected by a passageway 59 which, in turn, leads to a chamber 60 formed in the body 47 and bounded by the separator 26 and the wall 50.

In the operation of this last described modification of the invention, it will be seen that, in addition to the functions described with regard to Figure 1 that when pressure is applied to the passageway 39 the sleeve 26a and balls 36a will be released from engagement with the extension rod 23 as the piston 20 is moved to the left, as viewed in the drawings and that, likewise, when pressure is applied to the passageway 42 that the locking sleeve 25, balls 36 and tapered walls 41 will become disengaged from the extension rod 23 as the piston 27a is moved positively to the right, as viewed in the drawings.

With regard to the form of the invention shown in Figure 4, it will be seen that this construction is identical with that shown in Figure 3 but with the addition of recesses 60a and 61 formed in the portions 10 and 11 of the cylinder and the elongated ball races 62 and 63 of the separators

26 and 26a, respectively, and the addition of compression springs 64 and 65 bearing against the sleeves 25 and 25a, respectively, at one of their ends and against backing plates 66 and 67 at their other ends.

In the operation of this last-mentioned form of the invention, it will be apparent that in addition to the functions heretofore described with regard to Figure 3, that the springs 64 and 65 will function in the manner heretofore described with regard to Figure 2 of the drawings so that when the rod 16 is moved in either direction that the locking means will not function to release the piston rod extension 23 until the predetermined strength of either of the springs 64 or 65 has first been overcome.

While certain forms of the invention have been shown and described herein, it will be readily apparent to those skilled in the art that many minor modifications may be made without departing from the spirit of the invention or the scope of the appended claim.

What is claimed is:

A device of the character described comprising a cylinder, a dividing wall centrally disposed in said cylinder and forming the same into a first and a second compartment, a piston in the first compartment, a piston rod affixed to the piston and extending outwardly through one end of the cylinder, a secondary piston in said second compartment, an extension rod interconnecting the piston and secondary piston and extending through said dividing wall, a first locking sleeve surrounding the extension rod in said first compartment and having a frusto-conical inner wall tapering outwardly toward said piston, a cylindrical separator surrounding said extension rod within said first compartment, a ball race formed integrally with said separator and extending into the sleeve, balls in said race adapted to inter-

engage said extension rod and said frusto-conical inner wall when the separator and the sleeve are moved apart, a compression spring interposed between the sleeve and the race, a like sleeve reversely mounted in the second compartment, a like separator and ball race reversely mounted in the secondary compartment, balls mounted in said race and adapted to interengage said extension rod and said sleeve when the separator and the sleeve are moved apart, a compression spring interposed between the race and the sleeve, a conduit extending through the cylinder to a space therein defined by the dividing wall and the piston, a passageway in the walls of the cylinder interconnecting the said conduit and a space in the second compartment between the separator and the dividing wall, a secondary conduit in said cylinder connecting with a space between the secondary piston and the reversely mounted separator, and a secondary passageway interconnecting the secondary conduit and a space in the first compartment defined by the dividing wall and the separator in said first compartment.
